United States Patent Office.

ISAAC W. HART AND OMER NORTON, OF NEW BRITAIN, CONNECTICUT.

Letters Patent No. 74,352, dated February 11, 1868.

IMPROVED CARPET-FASTENER.

The Schedule referred to in these Letters Patent and making part of the same.

TO ALL WHOM IT MAY CONCERN:

Be it known that we, ISAAC W. HART and OMER NORTON, of New Britain, in the county of Hartford, and State of Connecticut, have invented a new and improved Carpet-Fastener; and we do hereby declare that the following is a full, clear, and exact description thereof, reference being had to the accompanying drawings, and to the letters of reference marked thereon.

Figure 1 shows a top view of the fastener as applied to a carpet.

Figure 2 shows a side view of the same.

Figure 3 shows a side view of the hook part A of the fastener, detached.

Figure 4 shows a side view of the leaf B, detached.

Figure 5 shows a front view of the part A.

Figure 6 shows a top view of the part A.

Figure 7 shows a top view of the part B.

Our invention consists in a carpet-fastener, formed of two pieces, A and B, in which A is formed of one piece of metal, cast or struck up in dies to the shape shown in figs. 3, 5, and 6 in the drawings, and B consists of a strip of sheet metal, of the form shown in figs. 4 and 7, which is secured under the piece A, and, after the carpet is hooked down, is folded over the edge, in the manner shown in figs. 1 and 2, to secure it in place. The part A is made with two hooks, *e e*, of a curved form, for hooking on the carpet, and two spikes or tacks, *d d*, which are driven into the floor to hold the fastener in its place. The tongue or leaf B is provided with two notches *e e* in its edges, through which the spikes *d d* pass, so as to secure the leaf B firmly in its place when the part A is driven into the floor. The part A can be made of brass or iron or any metal suitable for casting or swaging, and the part B of any rolled or sheet metal that has sufficient flexibility to withstand the necessary bending to take up and put down the carpet.

The operation of our invention is as follows: The part B is placed under the part A, and both secured to the floor by driving in the spikes *d d*, as shown in figs. 1 and 2. The leaf B is left bent upward, as shown in fig. 4. The carpet is then hooked over the points *e e*, and the leaf B bent down over its edge, holding it securely in its place.

By means of our invention a carpet can be taken up and replaced as often as desired, while the fastener remains permanently attached to the floor.

Claim.

What we claim as our invention, and desire to secure by Letters Patent, is—

The combination of the devices A and B for the purpose of a carpet-fastener, substantially as herein specified.

ISAAC W. HART,
OMER NORTON.
